Des. 200,622
Patented Mar. 16, 1965

200,622

LAVATORY FIXTURE

Loyd A. Whitener, Jr., Hickory, N.C., assignor to Drexel
Enterprises, Inc., Drexel, N.C., a corporation of
Delaware

Filed Apr. 30, 1962, Ser. No. 69,883

Term of patent 14 years

(Cl. D91—3)

FIG-3

FIGURE 1 is a perspective view of the lavatory fixture showing my new design;

FIGURE 2 is a front elevational view thereof; and

FIGURE 3 is another perspective view of the lavatory fixture as viewed from a position substantially opposite of FIGURE 1.

I claim:

The ornamental design for a lavatory fixture, as shown.
